UNITED STATES PATENT OFFICE.

JOHN H. MABIE, OF HOBOKEN, NEW JERSEY.

IMPROVEMENT IN COMBINED WATCH-CHAIN BARS AND PENCILS.

Specification forming part of Letters Patent No. 178,451, dated June 6, 1876; application filed March 11, 1876.

To all whom it may concern:

Be it known that I, JOHN H. MABIE, of Hoboken, in the county of Hudson and State of New Jersey, have a new and useful Combined Watch-Chain Bar and Pencil-Case; and I do hereby declare that the following is a full, clear, and exact description thereof.

My invention consists in a novel construction of a pencil-case, whereby the barrel of the pencil-case is made to serve as a watch-chain bar.

The invention is intended more particularly for application to what is known as an "extension pencil-case," in which provision is made for extending the length of the case when the pencil is used and contracting it when not in use. Such pencil-cases are of various kinds, some operating with what is known as a "screw-movement," and the extension and contraction being effected by a rotary motion imparted to one or more of the parts, and others operating with what is known as the "magic movement," and the extension and contraction being effected by a longitudinal motion imparted to one of the parts, which gives a like motion to another part in an opposite direction.

The accompanying drawing illustrates the application of my invention to a pencil-case of the latter description.

Figure 1 represents the combined watch-chain bar and pencil-case attached to a chain,

with the case contracted and forming the chain-bar. Fig. 2 represents the case extended, and the pencil ready for use.

The barrel A surrounds the movable parts in the usual or any suitable manner. About midway of its length it is provided with an eye, which may be formed on or attached to a ring or band surrounding the barrel, and said ring or band may be arranged to prevent any longitudinal motion of the barrel in the ring.

As shown herein, the eye b is attached directly to the barrel A. By means of the eye provision is made for the connection of the barrel to a watch-chain, to form a bar, and the eye may be connected to the chain by a ring, or attached directly to one of the links of the chain.

What I claim as new, and desire to secure by Letters Patent, is—

A combined watch-chain bar and pencil-case, in which the barrel of the pencil-case is made to constitute the bar, by having the eye for the connection of the chain attached to said barrel at or about midway of its length, and the pencil, when in use, is projected from the pencil-case, and when not in use, is drawn entirely within the case, substantially as herein described.

JOHN H. MABIE.
